UNITED STATES PATENT OFFICE.

ABRAHAM ASHKENAS, OF BROOKLYN, NEW YORK.

RESILIENT-CLIP BRACKET.

Application filed February 24, 1928. Serial No. 256,621.

This invention relates to supports and the improvements are directed to novel and improved means for removably attaching a panel to a standard shown in my co-pending application, Serial Number 238,806, filed December 9, 1927.

An important object of the invention resides in the provision of a device of the above-mentioned character, which is formed from a single piece of material, wire for instance, and adapted to form a union between a panel and a standard, as aforesaid.

Another object resides in the production of a support having one end formed to cooperate with a socketed end of said standard.

Still another object is to provide a device of the above character having a resilient clip portion at one end for removably clamping the marginal side of a panel.

20 A further object of the invention is to provide integral means intermediate the ends of said support upon which the bottom edge of a panel may abut and receive measurable support.

25 A still further object resides in forming the resilient clip portion of said support with a terminating lateral extension adapted to enter and abut the base portion of a notched panel. Other objects and features of the invention will become apparent in connection with the following description of one form of device embodying said invention and its operation.

35 The drawing illustrates an embodiment of my invention shown merely for the purpose of illustration and for affording an understanding of my invention, and not for limitation thereof, and it is to be understood that changes and modifications may be resorted to 40 within the scope of the appended claims without departing from the spirit of the invention.

In said drawing:

Figure 1 is an elevation of my novel and unique supporting clip, illustrating its application.

Fig. 2 is a top plan view thereof, the standard being shown in transverse section and its panel by dot and dash line;

Fig. 3 is a perspective view of the supporting clip; and

Figs. 4 and 5 are slightly modified forms of supporting clip.

Referring now more in particular to the accompanying drawings, wherein like characters of reference denote similar parts throughout the several views, the numeral 5

represents a panel adapted for association with a standard 6 carried by a base member 7, attachment between said standard 6 and base member 7 being preferably provided by 60 means of a pin 8, depending from the end of said standard and fitting into a bore 9, concentric with socket 7^a, in said base member 7. The construction of said standard is somewhat similar to that disclosed in my co-pending application aforesaid, and as shown in Fig. 2, the same is provided with a plurality of radially and longitudinally disposed slots 10, having tapering wall portions, into selected ones of which the edge of a panel may be 65 inserted to produce a screen having said panels disposed at varying angular positions. It will also be noted that the end portion of said standard 6, like unto said base member 7, is provided with a socket 11 into which the 70 lower portions of said slots 10 extend for a purpose to be hereinafter pointed out.

My resilient supporting clip comprises a body portion 12, preferably formed from a single piece of wire, one end of which being 80 bent laterally to define a hook 13, (see Figs. 2 and 3), which is insertible through a selected slot 10, for entry into said socket 11 for final positioning in a companion slot, as clearly shown in Fig. 2. The other end of 85 said body portion 12 is formed to define a pair of parallelly disposed circular portions 14, termed the clip portion, and which are adapted to be sprung apart laterally to clamp the marginal edge of said panel 5. This coiled 90 disposition provides a spring clamp which may be separated, due to its resilient nature, to secure panels of varying thicknesses, the other edge of said panel being inserted between the tapering walls of a selected slot 10 and maintained in the position shown in 95 Fig. 1.

While the device thus far disclosed admirably performs its functions, I have yet provided two additional features therefor, the 100 first comprising a lateral extension 15, forming the terminal of one end of the single piece of wire, and lying beneath the top convolutions of said circular portions 14. In view of this construction lateral displacement of a panel is positively precluded, since said lateral extension 15 is inserted in a slot 5^a in said panel, (see Fig. 1) and continues therein for final abutment against the bight portion of said slot. This is a feature of some importance. Further, I propose to offset said body portion 12, intermediate said clip portion 14 110

and hook 13, as indicated at 16, said offsets extending laterally and as shown in Fig. 2 an excellent supporting base is provided for the bottom edge of a panel.

5 While the supporting clip shown in Figs. 1 to 3 inclusive, depicts a hook portion 13 extending laterally to said body portion 12, I may provide a hook portion, (see Fig. 4), extending downwardly from said body portion 10 and having its vertical axis coinciding with the plane of the horizontal axis of said body portion. In this instance, said hook portion will be passed through a selected slot 10, as aforesaid, and finally engaged with the vertical wall portion of said socket 7^a, shown in Fig. 1. Also said hook portion may rise vertically from said body portion 12, (see Fig. 5) and engage with the walls of socket 11 of said standard 6.

20 In a screen, resolved to its simplest form of expression, two standards and one connecting panel will be used. In this construction four clips may be used, two adjacent each standard and mounted at the top and bottom 25 corners of said panel, and while said panels are firmly held in their respective positions their removal is easily effected in order to change the decorative features thereof, as is quite obvious.

30 The supporting clip is neat and attractive in appearance and in view of its relatively small proportions will not in any way detract from the appearance of the screens.

I claim:

35 1. A device of the character described and adapted to removably attach a panel to a standard, comprising a body portion having a hook at one end for attachment to said standard, and having its other end formed to define

a spring clip embodying a pair of parallelly 40 disposed circular portions adapted for lateral expansion for insertion of said panel.

2. A device of the character described embodying a body portion having a hook at one 45 end adapted to be secured to a standard, and having its other end formed to define a spring clip portion for removably attaching a panel to said standard, said body portion having a lateral offset intermediate said hook and said clip portion to provide a support for said 50 panel.

3. A device of the character described and adapted to removably attach a notched panel to a standard, comprising a single piece of 55 wire having a hook at one end for attachment to said standard and having its other end bent to define a pair of parallel resilient circular clip portions adapted to clamp the opposite sides of said panel, said clip portions terminating with a lateral extension adapted to enter the notch in said panel and abut the base thereof.

4. A device of the character described and adapted to removably attach a notched panel to a standard, comprising a single piece of 65 wire having a hook at one end for attachment to said standard and having its other end bent to define a pair of parallel resilient circular clip portions adapted to clamp the opposite sides of the panel, said clip portions 70 terminating with a lateral extension adapted to enter the notch in said panel and to abut the base thereof, the body portion having a lateral offset intermediate said hook and said 75 clip portions to provide a support for said panel.

In testimony whereof I affix my signature.

ABRAHAM ASHKENAS.
